RECEPTACLE

Alex M. Lewyt, Brooklyn, N. Y., assignor to Lewyt Corporation, Brooklyn, N. Y., a corporation of New York

Application June 4, 1949, Serial No. 97,221

2 Claims. (Cl. 206—10)

1

This invention relates to a structurally and functionally improved receptacle within which articles of various types may be stored.

It is an object of the invention to furnish a unit of this type, the interior and contained articles of which will have imparted to them a pleasing, desirable odor. Additionally, the interior of the receptacle may contain an insecticide in gaseous form so that if, for example, blankets or other materials are stored therein, they will not be injured by moth larvae.

An additional object is that of furnishing a container of this type which will embody a relatively simple construction, such that it may be manufactured at low cost; the receptacle moreover presenting a pleasing appearance and a structure which will operate over long periods of time without difficulties.

With these and other objects in mind, reference is had to the attached sheet of drawings illustrating one practical embodiment of the invention and in which:

Fig. 1 is a perspective view of a receptacle showing the same in open condition; and

Fig. 2 is a transverse sectional view taken along the line 2—2 and in the direction of the arrows as indicated in Fig. 1.

In these views the reference numeral 5 indicates the body of the receptacle which may be formed of any suitable material and to which a lid portion generally indicated at 6 is attached. Such attachment may be by hinging or in any other desired manner. Units such as have been indicated at 7, may be disposed within the receptacle body and embrace, for example, the several parts of a vacuum cleaner assembly. Obviously, any other desired articles may be thus stored, including for example, blankets, clothes, materials, etc.

Referring to the details of the lid structure as especially shown in Fig. 2, it will be seen that the latter preferably embraces a layer 8 which may be formed of wood and an underlying layer 9 suitably secured thereto which may be formed of fiber. The latter is formed with an opening or bore 10 at a point conveniently centrally of its face. Within this opening a receptacle 11 is disposed and which is preferably formed of metal. The base of this receptacle is perforated as indicated at 12. A central securing element such as a screw 13 may extend through the base and secure the receptacle or container 11 to layer 8. The interior of the receptacle may be filled with a mass of cotton 14 or other fibrous material which is suitable impregnated. Such im-

2

pregnation may be achieved by charging the fibrous mass with oil of cedar, or any other pleasing essence. As is apparent, there may also be included in this material a de-mothing substance should that be desired. At a point above the receptacle 11 the layer 8 is formed with one or more openings 15.

Layers 16 and 17 of a material which is conveniently leather-like in appearance may be employed and secured together by beading or edging strips 18. The side layers 17 of this flexible material are extended around the edges of the fibreboard layer 9 as indicated at 19. The inner face of that board layer may be covered as at 20 or otherwise left in natural condition. Layers or strips 17 and 20 may be affixed to the layers 8 and/or 9 in any desirable manner. A body of padding 21 is interposed between layer 16 and the wood or other layer 8. This padding should have resiliency such that it normally maintains the surface of layer 16 in an elevated condition as shown in Fig. 2.

As will be apparent, with lid 6 closed upon the receptacle body 5, a certain amount of gas emanating from the material contained within the shell or container 11 will pass to the interior of the receptacle. However, if pressure should be brought to bear upon the upper face of layer 16 then it is apparent that that layer will be depressed against the resiliency of the padding 21. The layers 16 and 17 being secured together to provide a substantially air-tight construction, it follows that the air contained within the padding will flow through opening 15 and so through the fibrous mass 14 and into the interior of the receptacle through the perforations 12. In such flow the entire interior of the receptacle will be permeated with the selected odor, insecticide or other material. Thus, no conscious effort will have to be exercised in assuring a proper distribution of the fumes.

Thus, among others, the several objects of the invention as specifically aforementioned are achieved. Obviously numerous changes in construction and rearrangement of the parts might be resorted to without departing from the spirit of the invention as defined by the claims.

I claim:

1. In a receptacle a substantially rigid body formed with an opening, a perforated casing to contain a suitable volatile agent, said casing being secured to the under face of said body in line with said opening, a layer of flexible, substantially air-impervious material spaced from and disposed above the upper surface of said body to

provide a deck portion and resilient material interposed between said body and layer and tending to maintain said layer in elevated position with respect to said body, whereby upon pressure being exerted against the upper layer face to 5 flex the latter towards the surface of said body, air will be forced through said opening and casing to be charged with the agent and will thence pass into the receptacle interior.

2. In a receptacle a substantially rigid body 10 formed with a recess in its inner face and an opening extending from the base of said recess through to the upper face of said body, a perforated casing to contain a suitable volatile agent, said casing being telescopically disposed with respect to said recess and secured to said body, a layer of flexible, substantially air-impervious material spaced from and disposed above the upper surface of said body to provide a deck portion and a body of resilient material interposed between 15 20

said rigid body and layer and tending to maintain the latter in elevated position with respect to said body, whereby upon pressure being exerted against the upper layer face to flex the latter towards the surface of said body, air will be forced through said opening and casing to be charged with the agent and will pass from said casing to the receptacle interior.
